MANUFACTURE OF GASOLINE

Eugene C. Herthel, Flossmoor, Ill., assignor to
 Sinclair Refining Company, New York, N. Y., a
 corporation of Maine

Application May 25, 1940, Serial No. 337,238

2 Claims. (Cl. 196—50)

This invention relates to improvements in the manufacture of gasoline of high anti-knock value by cracking petroleum stocks of lower anti-knock value in the presence of finely divided dispersed argillaceous materials which possess high adsorptive capacity and aid or direct the cracking reaction by catalysis. In particular the invention is concerned with improvements in that type of process in which a hydrocarbon stock a major portion of which boils within the boiling range of gasoline is subjected to that type of cracking commonly known as reforming whereby a substantial part of said stock is converted into gasoline material of improved anti-knock value.

Several methods for producing gasoline material of high anti-knock value, from high boiling petroleum stocks and from low boiling stocks of lesser anti-knock value, have been heretofore produced and used commercially to a considerable extent. However, such proposals have not been entirely satisfactory for a number of reasons. For example, it has been proposed to produce gasoline of high anti-knock value directly from high boiling petroleum stocks, such as gas oil and reduced crude, by severe thermal cracking. However, such operations invariably are accompanied by excessively high gas losses although such high gas losses are readily avoided in thermal cracking processes producing gasoline material of moderate or relatively low anti-knock value.

It has likewise been proposed to produce gasoline of high anti-knock value directly from high boiling petroleum stocks by thermal cracking aided by catalysis, in processes wherein the high boiling stock is vaporized and the vapors passed at a cracking temperature through a bed of catalytically active material. However, the active catalysts employed in such processes are costly and their efficiency active life is so short that regeneration of the catalyst bed at very short intervals is essential. The cost of such regeneration both from the standpoint of the initial cost of the equipment involved and its maintenance, the cost of carrying out the regenerating operation itself, and the limitations imposed on the useful operating time of the converting processes proper, all involve handicaps of major importance with respect to processes of this type.

A third proposal has involved thermally converting, or reforming, relatively low boiling stocks, a major part of which boils within the boiling range of gasoline, under severe cracking conditions. According to this proposal the low boiling charging material for the reforming operation may be either a distillate obtained from virgin stock or the crude product of the ordinary thermal cracking process carried out to produce gasoline material of relatively low anti-knock value. Operations of this type have been subject to serious limitations in continuity, due to the depo-

sition from the oil of heat insulating material on the interior surfaces of the conduit wherein the stock is heated to and at the cracking temperature, with resultant overheating of the walls of the conduit frequently accompanied by coke formation. The adverse effect of the deposition of such heat insulating materials is much more pronounced and more difficult to avoid in operations of this type than when cracking higher boiling materials such as gas oil.

I have devised a process by which the objectionable features of each of these prior proposals are substantially eliminated and several important additional advantages are derived. In the practice of my invention I admix a small proportion of a finely divided argillaceous material with a petroleum stock, a major part of which boils within the boiling range of gasoline, and heat this mixture to and at a high cracking temperature while flowing as a stream at a sufficient velocity to maintain said finely divided material in suspension in said stock, for a period of time sufficient to reform a substantial part of said stock to produce gasoline material of improved anti-knock value. Thereafter I separate a vapor fraction comprising said gasoline material from the resulting residual material comprising the residue of said finely divided argillaceous material. The residual material may be drawn off from the initial separating zone as a fluid mixture including the residue of the finely divided argillaceous material. Alternatively the residual material comprising the residue of the finely divided argillaceous material may be reduced in the initial vapor separating zone to a dry or substantially dry coke-like residue.

I employ as said petroleum stock a petroleum distillate of the requisite boiling characteristics produced by thermal cracking without catalysis. The boiling characteristics of this stock may be such that about 40% or somewhat less will distill off under superatmospheric pressure at temperatures up to 420° F. although stocks falling entirely within the gasoline boiling range may also be treated with advantage.

The finely divided argillaceous materials useful in the process of my invention include naturally occurring clays which have a limited catalytic action but exert a marked preferential adsorptive power for carbon forming materials, finely divided fuller's earth for example, as well as acid treated clays. They also include synthetic catalysts of high directive catalytic activity comprising silica and alumina, or silica and alumina together with other metal oxides such as oxides of zirconium, titanium, chromium, and the like, which are commonly used in catalytic cracking processes of the fixed bed type.

For use in the process of my invention the argillaceous materials are advantageously re-

duced to a powder the fineness of which may vary from about 100 mesh to an almost impalpable powder. However, particle sizes larger than 100 mesh may be used so long as the velocity of the oil is high enough to maintain the argillaceous material in a state of dispersion through the oil being treated during its entire passage through the heating conduit. Particle sizes considerably exceeding 100 mesh may be used satisfactorily under appropriate operating conditions especially when the argillaceous material is of very low apparent density as is the case with many aerogels. The use of larger particle sizes has the advantage that the larger particles may be recovered with less difficulty from entrainment in combustion gases in which they become dispersed in regenerating operations.

The process of my invention does not require expensive special apparatus and advantageously may be carried out in apparatus similar to that conventionally employed for vapor phase cracking processes or for combined vapor phase cracking and coking processes with only a minor amount of additional equipment. The temperatures and pressures useful in the practice of my invention may be similar to those employed in conventional thermal reforming operations. For example the mixture of oil and dispersed argillaceous material may be heated in the heating conduit to a temperature of 1050-1100° F. under a pressure of from 400-500 pounds per square inch. However, with synthetic argillaceous materials of high catalytic activity the optimum temperature may be as low as 950° F. The use of high pressures promotes increased capacity with a given apparatus but tends to limit the anti-knock value obtainable with moderate temperatures. Therefore, when using synthetic catalysts of high reforming activity and relatively low temperatures pressures as low as 50 pounds per square inch or somewhat less may be used with advantage.

The ratio of dispersed argillaceous material to oil will vary depending upon the nature of the oil to be treated, the particular argillaceous material employed and the desired anti-knock value of the eventual gasoline material. Amounts of finely divided argillaceous material varying from $\frac{1}{2}$ pound per barrel of oil, or somewhat less, to more than 12 pounds per barrel of oil, in the mixture as it enters the heating conduit, have been used with considerable success. Dispersion of a very small proportion of the argillaceous material through the oil being treated is effective in eliminating, or substantially reducing, the formation of heat insulating deposits on the interior surfaces of the heating conduit. The adsorptive action of the dispersed argillaceous particles for the more objectionable carbon-forming materials, e. g., tarry matter and polymers of high molecular weight, made effective substantially at the point of formation, appears in a large measure to be responsible for the elimination of heat insulating deposits in the heating conduit. However, the use of dispersed argillaceous materials in amounts substantially exceeding the minimum amount effective in substantially eliminating the formation of heat insulating deposits in the heating conduit is advantageous particularly when employing synthetic argillaceous material of high catalytic activity, since the additional argillaceous material aids and directs the reforming reaction in producing gasoline material of improved anti-knock value.

In the process of my invention the effectiveness

of the dispersed argillaceous material is promoted rather than impaired by the volatile character of the charging stock, since with charging stocks initially containing substantial proportions of high boiling hydrocarbons of high molecular weight the useful adsorptive capacity of the dispersed material is more rapidly exceeded and its catalytic action is masked to a greater extent by the larger quantity of adsorbed tarry matter.

- 10 By reducing the residual material to a substantially dry coke-like product including the residue of the finely divided argillaceous matter, any insufficiently cracked high boiling hydrocarbons may be recovered as a liquid substantially free from suspended matter, while the spent argillaceous material is recovered in a form especially adapted for efficient reactivation by burning. Moreover, the proportion of carbonaceous matter and vaporizable hydrocarbons present in the coke-like residue is so low that when using inexpensive naturally occurring argillaceous materials in my process, reactivation of the spent argillaceous material ceases to be a matter of economic necessity. Expensive regenerating equipment and the cost of regenerating operations may be dispensed with entirely in such instances.

Apparatus suitable for carrying out the process of my invention is illustrated, in a conventional diagrammatic manner, in the accompanying drawing and my invention will be further described in connection therewith.

Referring to the drawing a raw gasoline stock, or raw stock containing gasoline, is supplied from any convenient source of supply through line 1 to pump 2 by which it is forced through line 3, heat exchanger 4 and line 5 to the inlet of the heating conduit. A concentrated slurry of finely divided argillaceous material in oil is maintained in tank 8. Tank 8 is provided with a suitable 40 mechanical stirring device 9 adapted to prevent settling of the argillaceous material. This concentrated slurry is withdrawn from tank 8 by pump 10 and discharged through line 11 into the stream of raw charging stock passing through line 5.

The amount of concentrated slurry supplied in this manner is controlled by regulating the speed of pump 10 so that the mixture eventually entering the heating conduit from line 5 will include the desired predetermined proportion of argillaceous material. The heating conduit in this instance consists of two serially connected coils the first of which is disposed in furnace 6 and the second in furnace 7. A single furnace 55 may be used although serially connected coils disposed in separate furnaces have the advantage of permitting better control of the temperature gradient of the oil as it passes through the heating conduit.

60 The mixture of raw charging stock and finely divided argillaceous material may be heated in the heater 6 advantageously to a temperature of 850°-1100° F. and in the heater 7 to a temperature of 950°-1100° F. In the heater 7 the oil is maintained at a high cracking temperature for a period of time sufficient to reform a substantial part of said stock to produce gasoline material of improved anti-knock value. While passing through the heaters 6 and 7 the velocity of the flowing stream is maintained at a value high enough to preclude segregation and settling of the dispersed argillaceous material. The mixture of hot cracked products leaving heater 7 passes through transfer line 12 and pressure reducing valve 13 to receptacle 14 which may function

either as a coking receptacle or merely as a vapor-liquid separator. A by-pass line 15 communicating with valved branch lines 16 permits discharge of the products from the heater 7 at points of progressively increasing elevation when receptacle 14 is being used as a coke separating chamber and it is desired to minimize the back pressure on the heating conduit. In receptacle 14 the material discharged from the heater 7 separates into a vapor fraction and a residue including the residue of the argillaceous material present in the mixture supplied to heater 8. A relatively low pressure, for example, a pressure of 50 pounds per square inch or somewhat less is maintained in receptacle 14. A pressure of 400-500 pounds per square inch may be maintained on the oil at the outlet of the heater 7 and this pressure may be reduced at valve 13 (or at the valves in one or more of valved branches 16 if by-pass line 15 is being used). Vapors liberated in receptacle 14 are discharged through line 17 to the scrubbing tower 18. The liquid residue which accumulates in receptacle 14, when the temperature prevailing therein is insufficient for reduction to coke, may be drawn off through valved line 42 together with the dispersed residue of the argillaceous material.

In the scrubbing tower 18 high boiling tarry polymers are condensed and separated from the remaining vapors which continue on from the upper end of tower 18 through line 19. The intermediate portion of the scrubbing tower 18 may be provided with baffles 20 while several conventional bubble trays 21 are advantageously provided in the upper portion to guard against entrainment of tarry matter in the vapors leaving this tower through line 19. High boiling polymers accumulating in the lower part of scrubbing tower 18 are drawn off through line 22 by pump 23 and this material is returned, in whole or in part, to the upper end of receptacle 14 through line 24 to control the temperature of the initial vapor separating zone. When receptacle 14 is being operated as a coking receptacle, the tarry liquid thus supplied through line 24 performs the further function of assisting to maintain a liquid layer on the upper surface of the accumulating bed of coke. The hot vapors discharged from transfer line 12 are required to pass through this liquid layer on the upper surface of the accumulating coke bed, thereby separating and retaining in the coking receptacle the finer particles of dispersed argillaceous material which would otherwise be carried over to the scrubbing tower 18 by entrainment. When the chamber 14 is being operated as a coking receptacle, the temperature of the vapors in the upper part of this chamber may approximate 800°-825° F. Control of the temperature conditions in the scrubbing tower 18 may be maintained by supplying a cooling liquid through line 25, and branch lines 26 and 27, by means of pump 41. The temperature in the lower portion of the tower 18 may be varied from 650° F. to as high as 770° F. while the temperature in the upper portion may be varied from about 550° F. to 740° F. To the extent that high boiling tarry condensate accumulates in the lower end of tower 18 at a rate exceeding that which can be returned to receptacle 14 through line 24, and be either reduced to a cokey residue or reevaporated therein, such excess tarry condensate may be drawn off through valved line 28. Alternatively this condensate may be returned to chamber 14 to assist in providing the requisite additional cooling and

to assist in flushing out spent argillaceous material through discharge line 42 when receptacle 14 is to function merely as a vapor separator. When it is desired that the receptacle 14 function merely as a vapor separator an oil temperature not exceeding about 750° F. should be maintained in the lower end of receptacle 14 while the oil vapor temperature at the upper end should not exceed about 725° F.

10 Vapors discharged from scrubbing tower 18 through line 19 enter the lower end of fractionating tower 29 which may be of conventional bubble tower construction. Here the vapors are fractionated so that only those hydrocarbons suitable as components of the desired gasoline fraction, together with any lower boiling normally gaseous materials, will pass overhead through line 30 to condenser 31. The products from condenser 31 discharge into a conventional receiver 32 from the upper end of which gases are vented through line 33. Liquid condensate comprising the desired gasoline material of high anti-knock value is drawn off from the lower part of receiver 32 through line 34. A portion of this condensate 15 may be recirculated, via line 35, pump 36 and line 37, to the upper end of fractionating tower 29 to control the fractionating operation. The condensate which accumulates in the lower part of fractionating tower 29 is drawn off through line 38. This condensate may pass through the heat exchanger 4 wherein it gives up part of its contained heat to the raw gasoline stock by indirect heat exchange. The temperature prevailing at the upper end of the fractionating tower 35 29 may approximate 350°-410° F., depending on the desired end point of the final condensate. The temperature in the lower portion of this tower may vary from 500° F. to about 620° F. A portion of the condensate drawn off from tower 29 through line 38 and partially cooled in the heat exchanger 4 normally serves as the temperature controlling medium supplied by pump 41 to the scrubbing tower 18.

45 That part of the condensate from fractionating tower 29 not returned to the scrubbing tower 18 by pump 41 may be discharged from the system through line 39 or returned, in whole or in part, to the raw feed line 1 via connection 40 for recirculation through the heating conduit. Discharge of tarry matter from receptacle 14 through connection 42, of tarry condensate from scrubbing tower 18 through line 28, and of intermediate condensate from fractionating tower 29 through line 39 all have the effect of increasing the capacity of a given reforming unit but this increase in capacity is accompanied by a decrease in the maximum ultimate gasoline yield obtainable. Discharge of relatively volatile condensate from fractionating tower 29 through line 39 also has the effect of reducing the anti-knock value of the final product attainable with moderately severe heater conditions. This adverse effect on the anti-knock value of the final product can be counteracted by increasing the severity of the heater conditions although such increase is usually accompanied by an increase in the production of gas. On the other hand the discharge of heavy tarry matter in limited quantities from vapor separator 14 or scrubbing tower 18 appears to have no significant adverse effect on the anti-knock value of the final product.

60 It will be obvious that more than one coking receptacle may be provided so that the cokey deposit may be removed from one receptacle while another is being filled, thus also permitting the

coking modification of my reforming operation to be carried out as a continuous process. As soon as the operation of one receptacle has been discontinued, it may be steamed out in the usual manner by means of conventional steaming out connections (not shown) whereupon the coking receptacle may be opened and the cokey deposit removed. This deposit may be easily removed from the coking receptacle as it is less cohesive than the coke body produced in the usual coking operation. Normally the cokey residue resembles a caked powder which may be crushed or disintegrated with little difficulty.

A specific example of an operation embodying my invention as carried out with a particular charging stock in an apparatus of the type illustrated will further exemplify the invention: Using as the raw charging stock a distillate obtained from a paraffine base crude by moderately severe thermal cracking of the gas oil fraction, the distillate having an initial boiling point of 250° F. and with 60% and 90% distilling off up to 420° F. and 470° F., respectively; and as the reforming catalyst a synthetic argillaceous material composed of 85% silica and 15% alumina by weight prepared by precipitating aqueous sodium silicate with hydrochloric acid in the presence of added sodium chloride, adding aluminum chloride solution and precipitating with ammonium hydroxide, washing, drying at 250° F., crushing and sizing to 100 mesh, the illustrated apparatus may be operated in accordance with my invention in the following manner: A slurry of the raw charging oil and finely divided silica alumina catalyst above described is supplied at a rate regulated to maintain a ratio of 2.3 pounds of catalyst per barrel of oil in the mixture entering the heater 6. The rates of heating in furnaces 6 and 7 are controlled to maintain an oil temperature of 1050° F. at the outlet of the heater 6 and substantially the same oil temperature at the outlet of heater 7. An oil vapor temperature of 810° F. is maintained at the vapor outlet of receptacle 14. A pressure of 50 pounds per square inch is maintained in receptacle 14, while a pressure of 400 pounds per square inch is maintained at the outlet of the heater 7 by regulation of valve 13. All of the condensate from the scrubbing tower 18 is returned to receptacle 14 through line 24 and all of the condensate from the fractionating tower 29 not used in controlling the head temperature of the scrubbing tower 18 is recycled through the heaters 6 and 7 in admixture with the raw stock. Operating in the manner and under the conditions just described, there is produced approximately 80% of gasoline based on the raw charge. The gasoline thus produced will have an octane value of 77 as determined by the motor method. A solid cokey residue including the residue of the spent catalyst will deposit in receptacle 14 and this residue will contain about 35% carbon.

It will be apparent that in carrying out the process of my invention the ratio of catalyst to raw charging stock may be increased to a very high value without raising the ratio of catalyst to oil in the heating conduit to an extent high enough to preclude maintaining the catalyst in suspension, merely by progressively decreasing the conversion per pass and simultaneously increasing the recycle ratio. When using an active reforming catalyst and maintaining the heater

temperature, pressure and crack per pass at a value limited to maintain gas production at a minimum, an increase in the ratio of catalyst to oil increases the anti-knock value of the final product up to a point where an apparent anti-knock ceiling is reached. This appears to have been reached when the octane value approximates 77-78 as determined by the motor method.

As compared to catalytic processes of the fixed bed type, the plant costs for carrying out the process of my invention are exceedingly low. Moreover, the ratio of high octane gasoline produced to catalyst used is higher. Furthermore the ratios of high octane gasoline produced to coke formed and to catalyst used are higher in my process than those attainable by catalytic cracking of higher boiling oils such as gas oil. The higher gasoline yields per pound of catalyst involve a decrease in catalyst regenerating difficulties and costs.

I claim:

1. In the manufacture of gasoline of high anti-knock value, the improvement which comprises mixing a small proportion of a finely-divided 25 argillaceous material with a petroleum stock produced by thermal cracking without catalysis the major portion of which boils within the boiling range of gasoline, heating this mixture to and at a high cracking temperature approximating 950°- 30 1100° F. and under a pressure not substantially exceeding 500 pounds per square inch while flowing as a stream of sufficient velocity to maintain said argillaceous material in suspension in said stock for a period of time sufficient to reform 35 a substantial part of said stock to produce a gasoline material of improved anti-knock value, thereafter separating a vapor fraction comprising said gasoline material from the resulting residual material comprising the residue of said 40 argillaceous material, and limiting the maximum value of the crack per pass and the minimum value of the ratio of argillaceous material to oil in the mixture supplied to said heating to produce a gasoline product having an octane 45 number approximating 77 as determined by the motor method.

2. In the manufacture of gasoline of high anti-knock value, the improvement which comprises mixing a small proportion of a finely-divided 50 adsorptive catalyst with a petroleum stock produced by thermal cracking without catalysis the major portion of which boils within the boiling range of gasoline, heating this mixture to and at a high cracking temperature approximating 950°- 55 1100° F. and under a pressure not substantially exceeding 500 pounds per square inch while flowing as a stream of sufficient velocity to maintain said catalyst in suspension in said stock for a period of time sufficient to reform a substantial 60 part of said stock to produce a gasoline material of improved anti-knock value, thereafter separating a vapor fraction comprising said gasoline material from the resulting residual material comprising the residue of said catalyst, and limiting the maximum value of the crack per pass and the minimum value of the ratio of catalyst to oil in the mixture supplied to said heating to produce a gasoline product having an octane 65 number approximating 77 as determined by the 70 motor method.

EUGENE C. HERTHEL.
